SYNTHESIS OF ETHYLATED AROMATIC COMPOUNDS

Filed Feb. 13, 1943

UNITED STATES PATENT OFFICE

2,417,454

SYNTHESIS OF ETHYLATED AROMATIC COMPOUNDS

Ben Bennett Corson, Pittsburgh, and Lynn Joseph Brady, Ross Township, Allegheny County, Pa., assignors, by mesne assignments, to Koppers Company, Inc., a corporation of Delaware

Application February 13, 1943, Serial No. 475,752

15 Claims. (Cl. 260—671)

1
The present invention relates in general to the catalytic preparation of ethylated aromatic compounds more especially of the benzene series and is more particularly concerned with the synthesis of mono- and poly-ethylated benzene compounds from benzene hydrocarbons and ethylene, or a compound, such as ethanol, that yields ethylene under employed conditions of synthesis.

An object of the present invention is the provision of improvements whereby benzene, and hydrocarbons of the benzene series, can be easily and simply ethylated, in continuous operation, with either ethylene or ethanol, and whereby substantially only corresponding alkylated benzene hydrocarbons are produced; that is, benzene hydrocarbon compounds wherein the radical of alkylation has the same number of carbon atoms as the employed ethylene or ethanol.

A further object of invention is the provision of operating conditions and reactants' ratios that are suitable for employing a known catalyst for the stated purpose.

A further object of invention is the provision of commercially feasible operating conditions and reactants' ratios whereby the stated objects are realizable while at the same time preserving the chemical constitution of any uncombined reactants, that pass through the catalytic zone, in substantially such form that they can be recycled to said zone for retreatment to yield more of the stated products.

The invention has for further objects such other improvements and such other operative advantages or results as may be found to obtain in the processes or apparatus hereinafter described or claimed.

It has long been known in the art of petroleum refining that at elevated temperatures certain solid catalytic compositions had capacity for polymerizing unsaturated hydrocarbon compounds such as the olefines, and the like, of refinery gases and vapors into aliphatic derivatives of higher molecular weight and that the resultant mixture of hydrocarbon compounds contained new products that boiled within a range of temperatures which made them useful as motor fuels; it has also been further observed that, in the event the refinery gases and vapors contained aromatic compounds, which were either native to the cracking stock itself or were formed during its passage through a pyrolytic zone, or were introduced thereinto from an outside source, such aromatics were in some instances and in an indefinite manner alkylated during the polymerization of said gases and vapors, to yield

5 in the resultant product mixture, alkylated aromatics having boiling points that advantageously also permitted their inclusion in the finished motor fuel wherein they had value because of their ability to raise its octane number above that which would otherwise obtain.

10 The precise composition of a so-produced mixture containing alkylated aromatics was seldom investigated nor were the alkylated aromatics themselves closely identified or their yields determined. Neither was it established whether their presence resulted from a simple catalytic reaction between an aromatic hydrocarbon and an olefine, or the like, having the same number 15 of carbon atoms as the radical of alkylation, or resulted from olefinic reformation followed by alkylation, or from cracking of an aromatic compound that had been first alkylated with longer side-chains; such considerations being, indeed, 20 quite impertinent to purpose, method, or desired product.

25 Ethylbenzene has more recently become a valuable and important commodity by reason of its easy dehydrogenation, with high yield, to give a styrene product that is easily refinable or is sufficiently refined to be employed in the manufacture of one of the well-known forms of synthetic rubber. In consequence, the art of synthetic chemicals has more recently come urgently to require a cheap, convenient, direct, and continuous method of manufacturing ethylbenzene in such large quantities that its production as a mere incident in a confusion of other chemical reactions such, for example, as takes place in the 30 production of motor-fuel or in the carbonization of coal, where it represents a constituent in the light oil, or in the manufacture of carburetted water-gas, can no longer be considered an adequate or satisfactory supply-source.

35 40 Thus, a cheap, direct process that is adapted for continuous operation to convert the relatively plentiful compounds, benzene and ethylene, or ethanol, either into mono- or poly-ethylbenzene, is a distinct contribution to the art of synthetic chemicals; and such contribution is of especial value if the provided process avoids substantial destruction of reactants in secondary reactions such, for example, as pyrolysis, polymerization, or destructive alkylation, that would all reduce potential recoverable yields of the ethylated benzene or occasion subsequent complicated problems in the recovery and refining of the wanted pure product or products.

45 50 55 It has now been found that benzene can be directly and continuously alkylated, on a com-

mercial scale, with ethylene to give substantially only ethylated benzene in high yield when a mixture of benzene with at most about a molar equivalent of ethylene is passed, at relatively brief contact time, over a catalyst comprising a free acid of phosphorus, and especially over heat-treated orthophosphoric acid that is supported on a granular carrier, if the said catalytic agent is maintained at a temperature of at least about 260° C. and the said compounds are maintained under superatmospheric pressure of at least about 200 pounds per square inch. Importantly, it has been further discovered that, under the stated and similar conditions, the mixture of compounds effluent to the catalytic zone contain substantially only ethylated benzene and, except for a very minor portion, all of the original ethylene and benzene that have not participated in the said ethylation reaction, and that the latter are consequently in condition, after cooling and separation of the ethylated benzene, to be returned to the catalytic zone for retreatment and conversion to ethylated benzene. Thus, ultimately, by means of the present invention, a given quantity of either benzene or ethylene, can be converted to ethylated benzene with only relatively minor loss of said reactants.

It is interesting here to note and to emphasize for those skilled in the art that under the above-stated relatively mild operating conditions and when using as a catalyst an acid of phosphorus, the ethylation of benzene with ethylene itself can be performed, simply, straight-forwardly, and continuously without detectable polymerization of ethylene to longer chain aliphatic compounds and without loss of initial materials or the creation of complicated problems of product-separation and refining. The ethylation process of invention progresses without conversion of the ethylated benzene by pyrolytic decomposition into, for example, the toluene or xylene, or the like, such as is obtained as his product by Komarewsky, J. Am. Chem. Soc., vol. 59, p. 2715, (1937), who produced toluene as the end-product of the alkylation of benzene with ethylene in the presence of an alumina-nickel catalyst at 350° C. Neither is the ethylated benzene obtained in the manner of Sachanen, Jour. Ind. & Eng. Chem., vol. 33, page 1543, (1941), who obtained some ethylbenzene along with toluene, xylenes, and propyl- and butyl- and amylbenzene by the high temperature alkylation of benzene with amylene in the presence of activated clay, the ethylbenzene being formed as a mere incident of destructive alkylation of benzene with amylene. Ipatieff, Pines and Komarewsky, Jour. Ind. & Eng. Chem., vol. 28, p. 222-3, (1936), show that phosphoric acid, in liquid form, is operative after twelve hours of batchwise treatment, to convert benzene, that is sealed in an autoclave, into ethylated benzenes by means of ethylene. From the crude product of the reaction they were able to isolate several ethylated benzenes by a plurality of repeated, careful fractionations. The nature of the other and associated compounds in their crude reaction-product was not determined, but they probably belonged to the aliphatic and cyclic series of compounds because it is known that by treating ethylene alone with that catalyst which is also employed by the present inventors, such aliphatic, cyclic and the like compounds are formed, as is shown by Ipatieff and one of the present co-inventors in Jour. Ind. & Eng. Chem., vol. 28, p. 860 (1936).

According to the present invention, ethylation

of benzene and other aromatic compounds is effected by continuously flowing a mixture thereof with ethylene or ethanol over a catalyst that is formed by the deposition of preferably ortho-phosphoric acid on an inert carrier support such as Sil-O-Cel, Celite, or kieselguhr for example, said mixture containing not substantially more, and preferably substantially less, than a molecular equivalent of ethylene, or ethanol and said catalyst being maintained at a temperature of at least about 260° C. and the reactants at a pressure of at least 200 pounds per square inch. The said catalyst can be employed as a granular stationary mass or bed, or it can be continuously moved within or through the catalytic zone; and it is operative in either continuous or batchwise operation.

The yields of alkylated aromatic hydrocarbon produced in the practice of the present improvement, during a single pass of the ethylene-benzene mixture over the catalyst, vary with the temperature of the catalyst, the employed contact time, the ratio of benzene to alkylation agent and with the system pressure. It has been found that catalyst temperatures of from about 260°-300° C. give good conversions of benzene and ethylene, or ethanol, to ethylated benzene per single brief contact with the catalyst. It can, in general, be said that, other things being substantially equal, when the temperature of the catalyst is between 260°-300° C., an increased conversion of ethylating agent to alkylated aromatic per pass of reactants' mixture thereover results from increasing, either the contact time of such mixture with the catalyst, the ratio of benzene to alkylation agent, or the vapor pressure in the process-system, as will be evident from the hereinafter-given specific examples. Lower ratios of benzene to ethylating agent favor the formation of poly-ethylated benzenes. If the molar ratio of benzene to ethylene in the employed mixture of reactants is reduced to less than about 1:1, objectionable polymerization of ethylene with itself takes place with the consequent formation of unwanted compounds that are, for the present purpose, wasteful of the alkylating component.

Conversions of ethylene to ethylated benzene amounting to from 5-50% per pass of a mixture of refined ethylene and benzene over the catalyst have been obtained at contact times of respectively 14 to 61 seconds, when the catalyst was at a temperature of substantially 300° C.; conversions of over 70% of the ethylene have been obtained at the same said catalyst temperature and at a contact time of about 145 seconds when the benzene to ethylene ratio was as about 1.5:1.0. No evidence of the presence of substantial amounts of compounds of the type that could be produced by mere polymerization of ethylene to aliphatic compounds, or the like, of higher molecular weight, was detected in the reaction-products issuing from the zone of catalysis.

Exclusive of the ethylated benzene and the unreacted benzene itself, the gaseous and vaporous mixture effluent to the catalytic zone comprises over 97% of unreacted ethylene, about 2.3% of C₃ and C₄ hydrocarbons and substantially all of which were in the original ethylene employed, and about 0.3% of such permanent gases as hydrogen and methane. Thus, the ethylene not utilized for ethylation of aromatic hydrocarbon is in condition to be recycled directly to the catalytic zone with make-up ethylene without fear that alkylated products of unwanted constitution will be produced and which could present diffi-

cult problems in the refining of the wanted ethylated benzene. The unreacted ethylene can of course, if preferred, be refined, for example, by low-temperature fractionation, or the like, before it is recycled to the catalytic zone, for the purpose of removing its very minor content of other constituents and avoiding their possible accumulation in the process-system. There is evidence, however, that such step would be only rarely required, if ever. It is preferable but is not necessary to employ refined ethylene for the present improved process. It is, however, important to employ ethylene that is substantially free of olefines having a higher molecular weight, because, at the said favorable conditions for ethylenic alkylation, they exhibit a tendency either preferentially to react with the benzene, or to polymerize with themselves, or to pyrolyze indefinitely as do also any products of their direct alkylation of the benzene; they thus can produce products having lower molecular weight or specific gravity than the ethylated benzene, and pyrolysis gases formed therefrom are of such mixed and indefinite constitution that their direct recycling can lead only to production of a confused mixture of alkylated aromatics. The presence of hydrogen or methane in the ethylene is not deleterious, but if higher molecular weight olefines are present, they tend to make unpredictable the identity of the specific compounds that are synthesized by operation of the present improved process. It can in general be said that when alkylating benzene with any specific olefine to obtain an alkylated benzene having a radical of alkylation corresponding to said specific olefine, the employed olefine should be substantially free of other olefines, or the like, that exhibit greater tendency to unite with the benzene, if complicated recovery, purification, and even insoluble refining problems are to be obviated.

The employed ethylene can have any known source. It can, for example, be obtained from coke-oven gases or petroleum refinery gases either by their rectification or any preferred selective removal of other associated and interfering constituents. It may be also produced by the dehydration of ethanol, for example, by flowing the alcoholic vapor through comminuted coke or pumic stone carrying syrupy phosphoric acid (H_3PO_4) which is maintained at a temperature of approximately 300° C., as set forth in Backhaus No. 1,402,336, issued January 3, 1922, the so-formed ethylene being thereafter introduced into the benzene flowing toward the aforementioned catalyst chamber for alkylating said benzene therewith. It has also been found that a separate step for the dehydration of the ethanol to ethylene is not necessary when the presently employed catalyst for the alkylation reaction is phosphoric acid supported on Sil-O-Cel, kieselguhr, or the like, but rather that, at an effective temperature of about 300° C. for carrying out the alkylation of the present invention, the ethanol can be dehydrated in situ in contact with the benzene to be alkylated, and it is only necessary to flow an admixture of benzene and ethanol in appropriate molecular ratios over the catalyst, the water of dehydration of said alcohol having little effect on the catalyst activity at its effective temperatures for the instant novel synthesis.

The above-described process for ethylation of aromatic hydrocarbons is not only of merit for the preparation of mono-ethylbenzene but it is of utility in ethylating an alkylated benzene compound as is demonstrated by the fact that there is

produced by practice of the process both mono- and some poly-ethylated benzene even at very high ratios of benzene to ethylene, or ethanol, in the admixture carried over the catalyst mass.

5 It is also possible nuclearly to ethylate toluene, xylene, and the like, and also naphthalene or substituted derivatives thereof.

It is also advantageous to operate the present process at elevated pressures, as aforementioned; 10 for example, when the benzene-to-ethylene ratio is respectively about as 2.5:1 and at a contact time of about 55 seconds with the catalyst maintained at about 300° C., 22% of the ethylene was converted into ethylated benzene at a pressure of 200 pounds per square inch, whereas at a pressure of 400 pounds per square inch, other operating conditions remaining substantially the same, the conversion of ethylene to ethylated benzene averaged over 50% per pass for a continuous operating period of 24 hours.

The advantages of the present improvement and its features will be more clearly understood by reference to the accompanying drawing showing for purposes of exemplification a preferred apparatus and method in which the invention may be embodied and practiced but without limiting the claimed invention specifically to such illustrative instance or instances. In the single figure of the drawing, there is shown a diagrammatic elevational view, partly in vertical section, of said apparatus. It comprises essentially a well-insulated catalyst chamber 10 wherein there is supported a bed of granular phosphoric-acid catalyst prepared in the manner set forth in the hereinafter given Example 1, and columnar fractionating stills 20, 30, respectively for separating unreacted benzene and ethylene from process-products that pass from the catalyst-bed and for separating mono-ethylbenzene from poly-ethylbenzene manufactured by the activity of the presently employed catalyst. The said stills 20, 30, are each formed of a plurality of superposed bubble-cap trays.

45 In the practice of the process, benzene stored in tank 11 and supplied thereto through valved line 12 from a source thereof, is drawn into pipe 13 by pump 14 and by it forced under pressure into pipe 15, as indicated by the arrows, whence it passes into coiled pipe 16 of pipe-still 17. In coiled pipe 16, the stream of benzene is continuously preheated by heat delivered thereto by the combustion-products of fuel-gas burned at the nozzle end of fuel-gas delivery-pipe 18. The so-preheated benzene thereafter passes into pipe 19 and after passing through regulating-valve 19a, flows downwardly into the upper part of the tube 21 forming the walls of said catalyst chamber 10. Immediately before entering said tube, however, the preheated benzene is admixed with ethylene delivered by pipe 22 and is apportioned in preferred amount and pressure to such benzene by valve 23. The ethylene arrives in pipe 22 from its storage-tank 24 where it is held, under sufficient pressure, by means of pump 25, after delivery to the latter through line 26, to deliver it in required proportions to the preheated benzene passing into the catalyst chamber.

70 In the insulated catalyst chamber, the admixture of benzene and ethylene flows downwardly through the granular phosphoric-acid catalyst-bed contained therein and a portion of its ethylene and benzene contents is converted into ethylated benzene during its traversing thereof. Continuously leaving the lower part of the cata-

7
lyst bed, while further new quantities of said benzene-ethylene admixture are entering its upper surface, is a fluid stream containing the ethylated benzene, formed by the process, in admixture with still unreacted benzene and ethylene. This admixture passes through valved pipe 27 and is continuously discharged into the lower section of fractionating still 20 wherein, by means of heat supplied from indirect steam coils 28, the unreacted benzene and ethylene are fractionally distilled from the ethylated benzene which then flows through valved pipe 29 into receiver 31 therefor. The volatilized benzene and ethylene continuously pass upwardly through the fractionating column and are cooled in the presence of each other in condenser 32. This cooled mixture of benzene and ethylene is then continuously removed from said condenser by pump 33 in pipe 34 and by it increased in pressure sufficiently for it to flow into the downwardly extending section of said pipe 34 and to be discharged therefrom into admixture with the inflowing current of benzene continuously flowed, by the aforementioned pump 14, through pipe 15 and into preheating coils 16, and, in such admixture, the ethylene and benzene cooled in said condenser 32 again form a portion of the flow of ethylene-benzene admixture continuously flowed into contact with the bed of catalyst in catalyst-chamber 10.

The ethylated benzene, that is formed by the above-described synthesis and is separated from the said reactants in fractionating still 20, collects in the bottom of said still and in quantities controlled by the liquid-level control 35 of valve 36 of drain-pipe 29, passes into receiver 31 whence it is continuously removed by pump 37 and thereby forced into pipe 38 for delivery into the fractionating column of still 30 wherein the said ethylated-benzene product is continuously fractionated into mono-ethyl- and poly-ethylbenzenes by heat supplied to indirect heating coils 39, the mono-ethylbenzene being collected as over-head condensate in water-cooled condenser 40 whence it is drained by means of pipe 41 into a receiver 42 and thereafter to storage means through valved pipe 43. The higher-boiling poly-ethylated benzene product is separated as a liquid in the bottom of still 30 and is flowed therefrom, through valve 43 of pipe 44 by liquid-level control 45 for said valve, into receiver 46 and thereafter through pipe 47 into a provided storage.

In the event that the wanted ethylated-benzene derivative is the mono-ethylated product, poly-ethylbenzene collected in receiver 46 can, instead of being sent to storage, be returned to the catalyst-bed by opening valve 48 in pipe 49 and by means of pump 14 be admixed with benzene delivered from storage tank 11, the new admixture being thereafter preheated, as above-described, in pipe-still 16, and passed to the catalyst-bed which also has the ability to transfer one or more of the ethyl groups from the previously formed poly-ethylbenzene to the newly introduced benzene and thus to convert both compounds into mono-ethylbenzene. Or, if only poly-ethylbenzene is the wanted product of the synthesis, the hereinbefore mentioned mono-ethylbenzene delivered to its storage through pipe 43 from receiver 42 can be returned in similar manner to the catalyst-bed in admixture with additional ethylene and be there further ethylated to poly-ethylbenzene.

The following specific examples are illustrative of the results that can be obtained by means of

the present improvement, and present in considerable detail operating conditions that have been found useful in practice. In the examples, the expression "contact time" indicates the time required to displace that volume of the ethylene-aromatic hydrocarbon admixture present at any one instant in the void space of the catalyst-bed by another such volume of the admixture when its volume is determined in accordance with the simple gas-laws at the employed temperature of the catalyst and the pressure on the admixture of reactants.

Example 1

15 Five hundred parts of 85% ortho-phosphoric acid were thoroughly mixed with 117.5 parts of Sil-O-Cel along with a small amount of water to facilitate their mixing. This admixture was then dried in a muffle furnace at 275° C. for a total period of 28 hours after which it was screened in an atmosphere of relatively low humidity and the particles that passed through an 8-mesh screen and were retained on the 16-mesh screen were employed in the operations detailed in the following examples. The resultant catalyst contained phosphoric acid to the extent of 62%, expressed as P_2O_5 .

Example 2

30 A mixture of refined benzene and ethylene, said ethylene being 96.5% pure and containing a total of about 2.5% of ethane and C_3 and C_4 hydrocarbons along with 1% of a mixture of hydrogen and methane, was continuously flowed downwardly in vapor phase over a bed of the catalyst prepared as in Example 1 in the respective molal ratio of 1.8:1 under a pressure of 200 pounds per square inch, the catalyst bed being maintained at a temperature of 300° C. and the contact time of said vaporous mixture with the catalyst being about 59 seconds. The reaction-products effluent to the catalytic zone were cooled under pressure for condensation of the liquid products. The resultant gaseous and liquid mixture was then passed through stabilizer apparatus for the separation from the liquid products of the gaseous ethylene and that which was dissolved in said products. The so-separated ethylene showed upon analysis a purity in excess of 95% and was immediately returnable to the inlet of the process without further treatment. With each pass of the benzene-ethylene mixture over the catalyst bed, 22.6% of its ethylene component was converted to ethylated benzene which was easily separated in high purity from the unreacted benzene by simple fractionation in which the ethylated benzene was collected as the distillation residue. The so-recovered benzene was also in condition for recycling directly to the inlet of the process. The said distillation residue was then further fractionally distilled to a vapor temperature of 175° C. and thereby separated into two fractions; i. e. a distillate and a distillation residue. The distillate of mono-ethylbenzene boiled mainly at 133° C., uncorrected, and had a refractive index of 1.4957 N_D^{20} . The distillation residue, consisting mainly of poly-ethylbenzenes, had a refractive index of 1.5004 N_D^{20} . The described results represent 70 average operation for a period of 24 hours.

Example 3

In another example, a mixture of benzene and ethylene was continuously flowed in vapor form 75 for 16 hours, as described in Example 2, down-

wardly over a bed of the catalyst prepared as in Example 1, in the molal ratio of respectively 3:6:1. The contact time of the said mixture with the catalyst was increased from 59 to 86 seconds and the pressure on the vapors was increased from 200 to 400 pounds per square inch. The catalyst was maintained at 300° C. The average conversion of ethylene to ethylated benzene during this 16-hour period was 75%. The reaction products were separated as described in Example 2. The separated ethylene and benzene were again of such high purity that they were returnable to the inlet of the catalyst for re-treatment without concern that products other than ethylated benzene would result from their employment. By simple fractional distillation ethylated benzene, containing mono- and poly-ethylbenzene in the ratio respectively of 1:1.2 and having a refractive index of 1.497 N_D^{20} , was recovered.

Example 4

The following comparative process runs are delineated to show the results obtainable by the present novel process by varying the ethylene-to-benzene ratio while retaining other operating conditions substantially the same. In the following two runs the process was operated substantially in the manner described in Example 2. The phosphoric-acid catalyst, however, was of 6-10 mesh size. The results represent average figures over a 24-hour period.

Run No.	T., ° C.	Contact time, seconds	Pressure, p. s. i.	Molal ratio C_2H_6 / C_6H_6	Ethylene conversion per cent input	Weight ratio mono-ethylbenzene / poly-ethylbenzene
A-----	270	52	400	2.5	21	8.5
B-----	270	55	400	7.7	30	12.9

These runs A and B clearly show that, if desired, the ratio of mono- to poly-alkylated benzene can be easily varied by increasing the benzene-to-ethylene ratio in the reaction mixture flowed through the catalyst bed; they further show that, other conditions being equal, the said increase of said ratio increases the percentage of ethylene converted to ethylated benzene per pass of the reaction mixture over the catalyst.

Example 5

The following comparative process runs show the variation in results that are obtained by merely varying the pressure under which the mixture of ethylene and benzene vapors are flowed over the described phosphoric-acid catalyst.

The results set forth in the above-given examples clearly show that within the temperature range of activity of the said phosphoric-acid catalyst, increase of catalyst temperature, longer contact time of the reaction mixture of ethylene and benzene therewith, increase of pressure on the vapors of said reaction mixture during its contact with the catalyst, and increase of the benzene-to-ethylene ratio in the reaction mixture, each severally and all collectively tend to increase the percentage of a given quantity of ethylene that is converted into ethylated benzene per pass of an admixture of benzene therewith into contact with said catalyst. The said results also show that the greater the benzene-to-ethylene ratio in the initial reaction mixture, the less will be the amount of poly-ethylbenzene produced by the alkylation reaction.

It was further observed during the above-described investigation that whether or not the benzene-to-ethylene molal ratio, in the initial mixture of reactants, was as 1:1 or as 5:1, the unreacted ethylene effluent to the catalytic zone was always in excess of 95% purity, and that both it and the unreacted benzene were sufficiently pure to be immediately returned to the catalytic zone for additional treatment. No olefinic compounds of higher boiling point than ethylene were ever detected, by the potassium-permanganate test, in the synthetic liquid products after their stabilization.

Example 6

The present investigators also showed in the course of their studies that not only could the simple aromatic hydrocarbon, benzene, be ethylated under the above-described conditions but that an alkyl aromatic, for example toluene, responded to substantially the same operating conditions to yield ethyl toluene.

A mixture of pure toluene and refined ethylene in the molal ratio respectively of 2.3 to 1 was continuously flowed for a period of 24 hours through a bed of the phosphoric-acid catalyst, also prepared as in Example 1, under a pressure of 400 pounds per square inch, the said reaction mixture being in contact with the catalyst bed, which was maintained at a temperature of 300° C., for about 47 seconds. The reaction products

Run No.	T., ° C.	Contact time, seconds	Pressure, p. s. i.	Molal ratio $C_2H_6 / C_6H_5CH_3$	Ethylene conversion per cent input	Weight ratio mono-ethylbenzene / poly-ethylbenzene
C-----	300	52	200	2.6	22	6
D-----	300	61	400	2.4	50	7.5

These runs clearly show that if the pressure on the reactants is raised from 200 to 400 pounds per square inch, other conditions being substantially equal, the conversion of ethylene to ethylated benzene is more than doubled.

Comparison of runs A and C also shows that doubling the pressure on the reaction mixture is substantially equivalent to reducing the reaction temperature of the catalyst about 30° C.

leaving the catalytic zone showed upon analysis that an average of 32% of the ethylene was continuously converted to ethyl toluene and that under the stated conditions the monoethyl toluene was 7.9 times the poly-ethyl toluene produced by the reaction.

Example 7

The polycyclic aromatic hydrocarbon, naph-

11

thalene, was also ethylated by means of ethylene according to the improvement of the present invention.

A mixture of pure benzene, pure naphthalene, and refined ethylene, in the molal ratio of respectively 3:1:1 was continuously flowed, for a 24-hour period, downwardly through a bed of the phosphoric-acid catalyst, also prepared as in Example 1, under a pressure of 400 pounds per square inch, a given quantity of the reaction mixture being in contact with the catalyst bed, which was maintained at a temperature of 300° C., for about 53 seconds. The reaction-products leaving the catalytic zone showed upon analysis that an average of 19.5% of the ethylene entering the catalyst chamber was continuously employed for alkylation of both the benzene and the naphthalene and that the naphthalene was ethylated in preference to the benzene, 2.5% of the latter being converted to ethylbenzene per pass whereas 12% of the naphthalene was ethylated to ethylnaphthalene of which less than one tenth was in the form of poly-ethylnaphthalene. That portion of the ethylene which did not react with either benzene or naphthalene in the catalytic zone was of high purity and was suitable for directly recycling thereto to convert further quantities of benzene and naphthalene to ethylated derivatives thereof, and there was substantially no loss thereof in side reactions.

Example 8

In the following example, the employed ethylating agent was ethanol instead of the ethylene used in the above-given examples.

A mixture of benzene and 95% ethanol, in the molal ratio respectively of 10:1, was continuously flowed, for a 48-hour period, downwardly through a bed of the phosphoric-acid catalyst, prepared as described in Example 1, the said mixture being under a pressure of 400 pounds per square inch and being delivered to the catalyst, which was maintained at a temperature of 315° C., at such rate that it was in contact with the catalyst for about 96 seconds. The reaction products leaving the catalytic zone were substantially free of ethanol, an average of 29% thereof having been converted to ethylated benzene and the remainder into ethylene. Upon condensation and stabilization, as above described, of the reaction-products they were separated into a liquid fraction comprising, mono- and poly-ethylated benzene in the ratio, respectively, of 13:1, and a gaseous fraction consisting substantially only of ethylene which was useful for mixing with more benzene to synthesize additional ethylated benzene, in the manner described in the above examples, or for mixing with further quantities of benzene and ethanol to form a preferred ratio thereof for introduction into the catalytic zone. It is interesting here to note that water formed by the dehydration of the ethanol to form ethylene, in situ in contact with the benzene to be ethylated, did not interfere, under the stated operating conditions with the activity of the phosphoric-acid catalyst, and the so-formed water was easily separated from the above liquid fraction of the reaction-products and removed from the process system.

Example 9

In another specific example, a mixture of benzene and ethylene in the respective molal ratio of 15:1 was continuously flowed downwardly through a bed of the phosphoric-acid catalyst,

12

prepared as described in Example 1, the said mixture being under a pressure of 900 pounds per square inch. During the operating period, the catalyst-bed was maintained at a temperature of from about 260° C. to about 280° C., the maximum temperature obtaining locally at any one time was 296° C. Throughout the major portion of the run the catalyst temperature was held at substantially 280° C. in order to get benefit of the higher conversions of ethylene to ethylated benzene at this higher temperature. Adiabatic conditions were maintained in the catalyst chamber throughout. The treated benzene-ethylene mixture was preheated to substantially the above-mentioned temperatures before being brought into contact with the catalysts for conversion. The pressure on the process-products after they had passed through the catalyst chamber was reduced from 900 pounds to 50 pounds per square inch. Under this latter pressure, the process-products effluent to the catalyst were fractionally distilled to separate the unreacted ethylene and benzene from the ethylated benzene. The unreacted ethylene and benzene were then recycled to the catalyst inlet and re-employed for forming new quantities of ethylene-benzene mixture passed into the catalyst bed. When operating with the catalyst at a temperature of 260° C., the average conversion of ethylene, in the ethylene-benzene mixture, to ethylated benzene was about 66%, whereas, at 280° C., the conversion was 86.5%. The separated ethylated benzene showed upon analysis that it consisted of mono- and poly-ethylated benzene in the ratio respectively of 20:1. Over 100 pounds of benzene were ethylated, as described, per pound of catalyst up to the time the run was discontinued, and there was still no marked reduction in its activity. A total of over 1600 pounds of ethylated benzene was so prepared. The recycled ethylene separated from the ethylated benzene showed only a very minor content of gases other than ethylene; that is, a small percentage of methane and ethane, and they constituted impurities in the employed ethylene and do not represent side-reaction products of the process. They can be easily vented from the process system at their rate of accumulation. The ethylated benzene showed substantially no high-molecular weight aliphatic compounds, either saturated or unsaturated, and no unsaturated aromatic hydrocarbons.

Example 10

The results of the following process runs show the importance, for the present purpose, of maintaining the ratio of benzene to ethylene in the mixture thereof that is catalytically treated at not less than substantially 1:1. A mixture of benzene and ethylene containing these compounds in the ratio respectively of substantially 1:5 was flowed, under a pressure of 400 pounds per square inch and at a contact time of 54 seconds, over the phosphoric-acid catalyst which was maintained at a temperature of 300° C. The reaction products issuing from the catalyst chamber contained, in contrast to the above-given examples a significant proportion of constituents that boiled both considerably below benzene itself and also intermediate benzene and ethylbenzene. These constituents were not purely aromatic in nature as is shown by a refractive index as low as 1.438 N_D^{20} and a bromine number as high as 80.

When the ratio of benzene to ethylene was

changed so that they were present in their admixture in the ratio respectively of substantially 1:2 and the admixture was processed substantially as above described, the proportion of non-aromatic constituents in the mixture issuing from the catalyst chamber was importantly reduced, such constituents entirely disappearing when the benzene-to-ethylene ratio was altered so that they were present in substantially equimolecular ratio.

As shown by the above specific examples, the present improvement now makes possible the synthesis of substantially pure ethyl derivatives of aromatic hydrocarbons such as alkylbenzenes and even of benzene itself in continuous vaporous phase, or mixed liquid and vaporous phase operation, by reacting said aromatic hydrocarbons directly with ethylene, or ethanol, in the presence of phosphoric acid supported on a porous solid material such as Sil-O-Cel or the latter's equivalent. The novel process is simple and direct: only relatively short reaction times are required and it provides commercially feasible yields. Under the preferred conditions of operation, there is substantially no polymerization of the ethylene to purely aliphatic derivatives. Advantageously, there is neither significant pyrolysis either of the ethylene or of the aromatic hydrocarbon components of the reactants, nor of the wanted ethylene product of their reaction: the appearance of either of which phenomena would make unpredictable the yield or nature of the reaction products and could occasion difficult problems of subsequent recovery and refining of the wanted products, as well as being wasteful of reactants. The ethylene and aromatic hydrocarbon components of the reactants that do not take part in the said reaction following a single cycle of operation, are in condition for recycling to the process inlet for further treatment to give the wanted products. In short, the present improvement makes it possible to convert a given quantity of either ethylene, or ethanol, or of an aromatic hydrocarbon, substantially quantitatively into ethylated aromatic hydrocarbon.

The invention as hereinabove set forth is embodied in particular form and manner but may be variously embodied within the scope of the claims hereinafter made.

We claim:

1. A process for preparing predominantly only mono-ethyl benzene from a mixture of benzene and substantially pure ethylene, said process comprising: continuously and concurrently flowing in admixture benzene and substantially pure ethylene, with the molar ratio of benzene to ethylene greater than 1:1, into contact with a confined mass of a granular solid phosphoric acid alkylation catalyst that is maintained at a temperature between about 260°-315° C. and is adapted at said temperatures to react said ethylene with said benzene to form ethyl benzene; maintaining the reactants aforesaid in contact with said catalyst for a period of from about 14 to 145 seconds and at a pressure between 200 and 900 pounds pressure per sq. in. and thereby forming substantially only ethylated benzene and predominantly only mono-ethyl benzene from said reactants in contact with said catalyst; continuously displacing reactants from contact with said catalyst mass by aforesaid admixture flowing into contact therewith; and recovering mono-ethyl benzene from so displaced reactants.

2. A process as claimed in claim 1, and in

which the solid catalyst comprises an acid of phosphorus on a solid carrier for the same.

3. A process of ethylating benzene comprising: passing an admixture of substantially pure benzene and ethylene that is substantially free of olefine having a higher molecular weight, with the molar ratio of benzene to ethylene greater than 1:1, continuously through a solid phosphoric acid alkylating catalyst for a period of 14 to 145 seconds, at a temperature between 260° and 315° C., and at a pressure between 200 and 900 pounds per square inch, continuously withdrawing the reacted admixture from contact with said catalyst, separating the mono-ethyl benzene therefrom, and recycling any residual ethylene to the alkylation zone.

4. A process as claimed in claim 3 and in which the aforesaid admixture of pure benzene and ethylene is continuously passed through the catalyst in co-current flow.

5. A process of synthesizing an ethyl derivative of aromatic hydrocarbon, comprising, passing a mixture of aromatic hydrocarbon and ethylene that is substantially free of olefine having a higher molecular weight, with the molar ratio of aromatic hydrocarbon to ethylene greater than 1:1, continuously through a solid phosphoric acid alkylating catalyst for a period of 14 to 145 seconds, at a temperature between 260° and 315° C., and at a pressure between 200 and 900 pounds per square inch, continuously withdrawing the reacted admixture from contact with said catalyst, separating the mono-ethylated aromatic compound therefrom, and recycling the residual ethylene to the alkylation zone.

6. A process as claimed in claim 5, and in which the aforesaid admixture of aromatic hydrocarbon and ethylene is continuously passed through the catalyst in co-current flow.

7. A continuous process for preparing predominantly only mono-ethyl derivative of aromatic hydrocarbon from aromatic hydrocarbon and substantially pure ethylene, comprising: continuously flowing in admixture aromatic hydrocarbon and substantially pure ethylene into contact with a solid phosphoric acid catalyst that is at a temperature between about 260° C. and 315° C. and under pressure above 200 lbs. per square inch effective at that temperature for reacting said reactants to form mono-ethyl derivative of the aromatic hydrocarbon and that is substantially non-volatile and reactive within said temperature range to form mono-ethyl derivative of aromatic hydrocarbon from said reactants; continuously displacing reactants from contact with said catalyst by continuous flow of the aromatic hydrocarbon and ethylene components to be reacted into contact with the catalyst; recovering mono-ethyl derivative of aromatic hydrocarbon from the so displaced reactants; and maintaining the molar ratio of aromatic hydrocarbon to ethylene in the admixture in contact with the catalyst greater than 1:1, and the admixture in contact with the catalyst for a brief time of 14 to 145 seconds, and thereby forming predominantly only monoethyl derivative of aromatic from the reactants as the product of the process.

8. A process as claimed in claim 7, and in which the catalyst comprises an acid of phosphorous supported on a bed of carrier solids therefor.

9. A method as claimed in claim 7, and which includes the steps of separating mono-ethylated and poly-ethylated aromatic hydrocarbons in the so-displaced reactants from each other, and re-

15

turning the poly-ethylated aromatic hydrocarbon in admixture with aromatic hydrocarbon into contact with said catalyst as aforesaid, and thereby converting the former into less extensively ethylated aromatic hydrocarbon.

10. A method as claimed in claim 7, and in which the aromatic component and the ethylene component are introduced to the catalyst as a preformed admixture in the molar ratio to be reacted within the range set forth in claim 7, and in which the ethylene component is introduced as ethanol, and ethylene is formed in situ in the catalyst zone from the ethanol by dehydration thereof.

11. A process as claimed in claim 7, and in which the aromatic component and the ethylene component are introduced to the catalyst as a preformed admixture in the molar ratio to be reacted within the range set forth in claim 7, and in which the ethylene component is introduced as ethylene.

12. An improved process for synthesizing predominantly only mono-ethyl derivative of aromatic hydrocarbon, comprising: reacting an admixture of substantially pure aromatic hydrocarbon with ethylene that is substantially free of olefine having a higher molecular weight while continuously passing in fluid phase in contact with a solid phosphoric acid catalyst that is effective to promote the alkylation of said aromatic hydrocarbon with said ethylene and that is non-volatile under the following conditions of temperature and pressure; maintaining said mixture in contact with said catalyst for a period of 14 to 145 seconds, the catalyst at least about 260° C., the ratio of ethylene to aromatic at most not more than a substantially equi-molecular ratio, and superatmospheric pressure between 200 and 900 lbs. per square inch on said ethylene and aromatic component, while passing in contact with said catalyst; and thereby converting a substantial portion of said admixtures content into substantially only ethylated aromatic hydrocarbons and predominantly only mono-ethyl-

16

ated aromatic hydrocarbon; and simultaneously continuously passing the reacted mixture consisting of predominantly only mono-ethylated aromatic hydrocarbon, unconverted aromatic hydrocarbon, and residual unconverted ethylene from contact with said catalyst.

13. A method as claimed in claim 12, and in which the aromatic hydrocarbon is benzene.

14. A method as claimed in claim 12, and in which the aromatic hydrocarbon is toluene.

15. A method as claimed in claim 12, and in which the aromatic hydrocarbon is naphthalene.
